UNITED STATES PATENT OFFICE.

EDWARD CALUSINSKI, OF CHICAGO, ILLINOIS.

UMBRELLA.

1,264,010.

Specification of Letters Patent. Patented Apr. 23, 1918.

Application filed November 10, 1917. Serial No. 201,295.

To all whom it may concern:

Be it known that I, EDWARD CALUSINSKI, a citizen of the United States, and a resident of Chicago, in the county of Cook and State 5 of Illinois, have invented a new and Improved Umbrella, of which the following is a full, clear, and exact description.

Among the principal objects which the present invention has in view are: to provide a structure of the character mentioned, 10 which may be folded within small compass; to simplify the operation of folding an umbrella so constructed; and to strengthen the construction.

15

Drawings.

Figure 1 is a vertical side elevation of a fragment of an umbrella frame constructed and arranged in accordance with the present invention, the parts being shown as disposed when the frame is spread;

Fig. 2 is a view of certain of the parts disclosed in Fig. 1 and shown in a partially folded position;

Fig. 3 is a vertical section on an enlarged scale of the telescopic members forming a portion of the cane shown in Fig. 2;

Fig. 4 is a detail view showing in perspective, the hinge forming the junction of two parts of the folding braces;

Fig. 5 is a view showing the upper end of the umbrella cane and a rib of the umbrella folded;

Fig. 6 is a detail view showing hinged ends of sections of the rib;

Fig. 7 is a detail view showing in perspective, a sliding hinge member with which the brace is provided.

40

Description.

As seen in the drawings, umbrellas constructed and arranged in accordance with the present invention have ribs formed of three sections. The inner section 12 is operatively connected with an end section 13 by means of a median section 14. The sections 12 and 13 are connected with the said median section by means of pins 15 and 16, respectively. The end section 13 is maintained in proper alignment with the median section 14 by a brace section 17. The brace section 17 is pivotally connected by a pin 18,

with a bracket 19 rigidly secured to the section 13. The inner end of the bracket 19 is slightly curved in correspondence with the 55 curved end 20 of the median section 14.

The end of the brace section 17 opposite to that attached to the bracket 19, is pivotally connected to a sliding loop 21. The loop 21 moves lengthwise of the median section 14. The pin 22 which secures the brace section 17 to the loop 21, also holds pivotally connected with the said loop, a short arm 23.

As seen best in Fig. 4 of the drawings, the 65 arm 23 has an offset 24, the end whereof is pivoted by means of a pin 25, to a bifurcated offset 26 integrally formed with the brace section 27. The section 27 is pivotally mounted in a crown ring 28, said ring being 70 shaped in conformity with the crown ring 29, to which the inner section 12 of the umbrella rib is pivotally attached. The means for attaching the brace 27 and the section 12 to their respective crown ring, is that employed in the usual construction of umbrellas.

To steady the construction and more particularly the outer terminal of the section 12, a spreader brace 30 is pivotally secured to 80 the section 12 and to a bracket 31 mounted on the brace section 27.

The crown rings 28, 29 and 32 are fixedly mounted on tubular sections 33 and 34 and the sleeve 35. The sections 33 and 34 are 85 telescopically united, the sleeve 35 being slidably mounted on the section 33 and supported and guided in its movement thereon by a pin 36 and a slot 37 formed in said section 33.

The sleeve 35 is operatively connected with the brace section 27 by spreading rods 38. The rods 38 are each pivotally connected with a fixed clip 39 on the section 27.

The tubular section 33 at the lower end, 95 has a screw-threaded section 40, the threads whereof register with threads formed in the end of the cane 41, which has a handle 42. The combined length of the cane 41 and handle 42 equals the combined length of the 100 tubular sections 33 and 34 when the same are folded to the position shown in Fig. 5 of the drawings. It will be understood that when folding the umbrella for storage or

transportation, the cane is disengaged from the section 33 and is overlaid upon the package formed by the telescoped sections 33 and 34 and the folded ribs and braces therefor.

5 As shown best in Fig. 5 of the drawings, the short arm 23, and offsets 24 and 26 thereof, when folded, envelop the rib sections 12 and 14 and the spreader brace 30. The offsets 24 and 26 are alined to accommodate the disposition of the rib sections and brace when folded.

10 It will also be observed that a similar office is performed by the curved portions of the bracket 19 and curved end 20 for the brace section 17 and short arm 23. By reference to Fig. 5 of the drawings, it will be seen that the curved portions of the said bracket and curved end maintain the sections 13 and 14 in spaced relation to permit the unleashing therebetween of the said brace section and short arm.

15 The cover for the umbrella frame may be permanently secured to the ribs and sections thereof. Care is exercised to secure said cover to the sections 12, 13 and 14 and to the pivoted junctions thereof so that the cover juxtaposed to these junctions will be moved therewith to carry the portion of the cover to which they are connected in conformity with the disposition of the rib sections.

20 To place the umbrella in service, the cane 41 is preliminarily secured to the tubular section 33. The operator holding the handle 42 in one hand, with the other hand moves the sleeve 35 outward along the sleeve 33, being guided in its movement by the slot 37. Each of the rods 38 presses upon one of the brace sections 27 and parts connected therewith to elevate the tubular section 34 and crown ring 29 connected therewith until the same is in the position shown in Fig. 1.

25 During the movement of the section 34 and partly inducing the same, the rib section 12 is spread to its outer position and the sections 14 and 13 are relatively unfolded and straightened to form with the section 12, the slightly curved rib structure shown in the drawings. The section 14 is induced to unfold from the section 13, swinging on the pivot pin 15 by the pressure exerted by the spreader bar 30 on the one hand, and the pull exerted by the short arm 23 and brace 27 on the other, said pull being applied to the loops 21. The sections 13 are moved relatively to the sections 14 from the position shown in Fig. 1 of the drawings, to the positions shown successively in Figs. 30 2 and 5, by the brace section 17, which is drawn lengthwise of the rib section 14 by the pressure exerted thereon.

It will be understood that the various operations thus detailed occur simultaneously

and as far as the operator is concerned, the 35 opening of an umbrella constructed and arranged in accordance with the present invention, resembles the operation performed in unfolding the conventional umbrella. When the sleeve 35 is raised to the upper 70 end of the slot 37, the pin 36 passes around the hook end 44 and rests in the depressed end 35 of said hook end.

When it is desired to lower the umbrella, the sleeve 35 is manipulated to lift the pin 75 36 out of the depressed end 45 of the slot 37. The sleeve is then drawn down on the section 33 until the pin 36 is disposed at the lower end of the slot 37. During this movement, it will be noted that the rod 38 80 depresses the outer end of the brace section 27, so that the tubular section 34 is depressed and the various parts of the ribs and brace construction are drawn to the position shown in Fig. 5 of the drawings. 85

Claims.

1. An umbrella comprising a plurality of ribs, said ribs embodying three pivotally connected sections, the middle section being 90 arranged to fold on the connecting sections from opposite ends thereof, a plurality of braces, each brace having three pivotally connected sections, the end sections of each of said braces forming lateral inclosing members for one of said ribs when folded, and a plurality of connecting members operatively connecting the sections of said braces and the sections of said ribs to cause said ribs and said brace sections to operate in 95 correspondence.

2. An umbrella comprising a plurality of ribs, said ribs embodying three pivotally connected sections, the middle section being arranged to fold in the connecting sections from opposite ends thereof, a plurality of braces, each brace having three pivotally connected sections, the end sections of each of said braces forming lateral inclosing members for one of said ribs when folded, 110 a plurality of connecting members operatively connecting the sections of said braces and the sections of said ribs to cause said ribs and said brace sections to operate in 115 correspondence, and means for raising and lowering the inner ends of said braces for spreading said braces and ribs connected therewith.

3. An umbrella comprising a plurality of ribs, said ribs embodying three pivotally connected sections, the middle section being arranged to fold on the connecting sections from opposite ends thereof, a plurality of braces, each brace having three pivotally connected sections, the end sections of each of said braces forming lateral inclosing members for one of said ribs when folded, 120 a plurality of connecting members oper-

atively connecting the sections of said braces and the sections of said ribs to cause said ribs and said brace sections to operate in correspondence, means for raising and lowering the inner ends of said braces for spreading said braces and ribs connected therewith, and means for locking said braces

and the inner ends thereof in position to maintain the spread relation of said ribs and said braces.
